UNITED STATES PATENT OFFICE.

CHARLES E. LUCKE, OF NEW YORK, N. Y., ASSIGNOR TO WORTHINGTON PUMP AND MACHINERY CORPORATION, OF NEW YORK, N. Y., A CORPORATION OF VIRGINIA.

CONDENSER.

Application filed February 8, 1927. Serial No. 166,780.

This invention relates to steam condensers of the surface type and an object of the invention is to provide a construction of high vacuum surface condenser adapted especially for large sizes, in which each of the condenser tubes contributes the maximum area possible to active condensation of steam, and thus reduces to a minimum the total tube surface required for a given rate of steam per hour.

In carrying out the invention one of the aims is to minimize the pressure drop between the tubes in the steam and air zones by a short and equal path and by causing the steam to sweep all of the tube surfaces substantially equally, so as to prevent any sluggish flow in any region, and to equalize the pressure drop across the steam flow paths between the tubes throughout the condenser by making all these steam paths substantially equal in flow resistance. It is also aimed, to present to the incoming steam a large percentage of the total condenser tubes so as to secure the maximum of condensing activity and to make this percentage of tubes presented to the incoming steam substantially constant and independent of the size of the condenser.

In attaining these objects, the condenser tubes are disposed in the form of a belt through which the exhaust steam passes from one side to the other, the flow resistance through this belt being uniform so that the steam will not pass through portions of the belt more freely than through other portions. The tubes in the belt may be uniform in number and spacing of tubes from the entrance side to the exit side, or the tubes may be spaced more closely on the exit side, it being necessary only that the flow resistance from the inlet to the outlet side should be the same throughout the length of the belt. Other means, however, may be employed for securing the uniform resistance of flow across the belt that is important for securing the result of uniform flow and maximum condensation from each of the tubes. This desired result of uniform flow and maximum condensation from each of the tubes may be secured by a thinner belt of tubes closely spaced or a thicker belt of tubes more widely spaced, and the belt need not be continuous throughout the condenser, but may be interrupted by a plate or plates without destroying the uniform flow resistance through

the active portion of the tube belt. The belt will preferably be formed in folds or convolutions to provide large tube area within a certain condenser dimension with free admission of steam to a large percentage of the tube surface, and these folds or convolutions may be of any suitable shape and adapted to a shell of any desired form. The folds or convolutions will be so arranged as to provide equal access of steam to all the tubes of the outer row on the steam side of the belt and so as to provide equal freedom of escape of air from all the tubes on the outlet or air side of the belt. It is preferable that all steam flow areas should be proportioned to the number of tubes supplied by steam from any particular section of the steam flow passage, so that the steam velocity will be the same in entering the tube belt and likewise the air spaces between the tube folds will preferably be widest at the exit end of the air passage, which aids in securing a compact construction and reducing the total size of the condenser.

In the present application the general features of the invention above described are used in condensers in which special provision is made for preventing contact of the condensate with air left by condensation of steam and for delivering the condensate to the hot-well at a temperature as near the temperature of the exhaust steam as possible.

A further and particular object of the present invention is, therefore, to provide for passage of the steam approaching and entering the tube belt by way of any steam lane in a generally upward direction so that condensate guide plates extending across the tube belt will drain the condensate towards the steam zone and thence to the hot-well thereby maintaining the condensate at a high temperature and at the same time preventing contact of the condensate with the air at the outlet side of the tube belt, which air preferably is drawn off through a suitable air outlet near the steam inlet and protected therefrom by the steam guiding baffle.

With these objects in view, the invention consists in various features of construction and combination of parts, which will be first described in connection with the accompanying drawings, showing a condenser of the preferred form embodying the invention, and the features forming the invention will be specifically pointed out in the claims.

In the drawings—

Figure 1 is a diagrammatic cross-sectional view through one form of condenser showing the air cooler housed within the condenser shell.

Figure 2 is a diagrammatic cross-sectional view through a modified form of the condenser and showing an exterior air cooler.

Referring more particularly to the drawings, the condenser includes the shell 1 having the exhaust inlet 2, hot-well 3 and air outlet 4. The air outlet 4 is positioned near the center of the steam inlet 2 and is protected from the incoming steam by the plate 5. The plate 5 inclines downwardly in both directions from the center of the exhaust inlet 2 and directs the incoming steam towards the sides of the condenser and towards the hot-well 3. A belt 6 of tubes, which is arranged in folds providing steam spaces or lanes 7 on the inlet sides of the folds and air spaces or lanes 8 on the exit sides of the folds, extends from one inner edge of the plate 5 across the condenser to the other edge of the plate forming a belt of tubes between the hot-well 3 and the air outlet 4. The steam entering the condenser is directed by the plate 5 around the inside of the condenser shell so that it passes inwardly through the tube belt 6 from the sides and from steam lanes that extend upward in a direction opposite to its direction of entrance into the condenser and the air is taken off from the innermost point of the space confined between the tube belt 6 and plate 5. A plurality of inclined condensate guide plates 9 extend across the folds of the tube belt 6 at pre-determined positions and divide the tube belt into horizontal inclined sections, while vertical splash plates 10 extend longitudinally through the steam lanes. It will be noted that the inclined condensate guide plates 9 in the inner folds or sections of the tube belt on each side of the vertical splash plates 10 incline downward towards the vertical splash plates while the inclined condensate guide plates 9 in the outermost folds or sections of the tube belt incline downward towards the shell 1 of the condenser. The plates 9 and 10 which need not be continuous as shown, are arranged so as to direct the condensate into the steam entering the tube belt or into the steam having the highest temperature and least air without drawing it into the air spaces 8 and preventing it, while falling, from contacting with many tubes. The advantage of this is, first that the condensate passing into the steam entering the tube belt is heated or attains the maximum temperature and the necessity of special provisions for re-heating the condensate is eliminated, and second, that it is a well-known and proven fact that the temperature of the steam at various points in the condenser lowers as the propor-

tion of steam in the mixture of steam and air is reduced in the course of its condensation from the steam entrance to the air pump suction so that by directing the condensate away from the air pump suction or the air outlet 4 and away from the zones which are colder than the others, decrease in the temperature of the condensate and also its absorption of air are both prevented.

In Figure 1 of the drawings a section 11 of tubes is provided in forming an air cooler for cooling the air before it is drawn out of the condenser while in Figure 2 of the drawings an air cooler 20 of any approved construction which is exterior to the condenser shell is illustrated. The air is drawn into the cooler 20 and passes therethrough, exiting to the air ejector or vacuum pump of any approved form through the outlet 21.

The construction of the condenser illustrated in Figure 2 is similar to the construction shown in Figure 1 differing therefrom, first in that the air cooler is outside of the condenser shell and second, in that the tube belt 26 is provided with fewer folds than the tube belt 6 and consequently a smaller number of vertical plates is required and would normally be suitable for a smaller size.

It will be understood that the invention is not to be limited to the specific construction or arrangement of parts shown but that these may be modified widely within the invention defined by the claims.

What is claimed is:

1. In a surface condenser having tubes arranged in a belt to form vertically extending sections, a plurality of horizontally inclined condensate guide plates across said tube belt for receiving the condensate from the section of tubes immediately above and discharging said condensate into the steam entering the tube belt.

2. In a surface condenser having tubes arranged in a belt and in folds to provide vertically extending sections having steam lanes on the inlet sides of the folds, a plurality of horizontally inclined condensate guide plates across said belt for receiving the condensate from the section of the tubes immediately above each plate and discharging such condensate into the steam entering the tube belt.

3. In a surface condenser having tubes arranged in a belt and in folds to provide vertically extending sections having steam lanes on the inlet sides of the folds, a plurality of horizontally inclined condensate guide plates across said belt for receiving the condensate from the section of the tubes immediately above each plate and discharging such condensate into the steam entering the tube belt, the horizontally inclined condensate guide plates in the alternate sections of the belt inclining downwardly in one direction and the condensate guide

- plates in the adjacent sections inclining downwardly in opposite directions.
4. In a surface condenser having tubes arranged in a belt to form vertically extending sections, a plurality of horizontally inclined condensate guide plates across said tube belt for receiving the condensate from the section of tubes immediately above and discharging said condensate into the steam entering the tube belt, and means for directing the incoming steam towards the sides and the bottom of the condenser whereby the steam will be directed inwardly and upwardly through the tube belt.
5. In a surface condenser, a tube bank consisting of a belt of tubes, means for directing steam through said tube belt in a direction reversely to the direction of entrance of steam into the condenser, and means for directing condensate from said belt of tubes through the steam entering the tube belt.
6. In a surface condenser, a plate inclining downwardly from the center of the steam inlet of the condenser, an air outlet at the inner side of the apex of said plate, and a belt of tubes extending across the condenser from one edge of said plate to the other, whereby steam entering the condenser will be directed towards the sides and bottom of the condenser and will flow inwardly and upwardly through the tube belt towards the air outlet.
7. In a surface condenser, a plate inclining downwardly from the center of the steam inlet of the condenser, an air outlet at the inner side of the apex of said plate, a belt of tubes extending across the condenser from one edge of said plate to the other, whereby steam entering the condenser will be directed towards the sides and bottom of the condenser and will flow inwardly and upwardly through the tube belt towards the air outlet, and a plurality of horizontally inclined condensate guiding plates across said tube belt for receiving the condensate from the section of tubes immediately thereabove and discharging said condensate into the steam entering the tube belt.
8. In a surface condenser, a plate inclining downwardly from the center of the steam inlet of the condenser, an air outlet at the inner side of the apex of said plate, a belt of tubes extending across the condenser from one edge of said plate to the other, whereby steam entering the condenser will be directed towards the sides and bottom of the condenser and will flow inwardly and upwardly through the tube belt towards the air outlet, and a plurality of horizontally inclined condensate guiding plates across said tube belt for receiving the condensate from the section of tubes immediately thereabove and discharging said condensate into the steam entering the tube belt.
9. In a surface condenser having tubes arranged to form vertically extending sections with steam lanes on their inlet sides and air lanes on their exit sides, a plurality of horizontally inclined condensate guiding plates across said tube belt and inclining downwardly towards said steam lanes, said condensate guiding plates provided for receiving the condensate from the section of tubes immediately above and discharging said condensate into the steam entering the tube belt.
10. In a surface condenser having tubes arranged to form vertically extending sections with steam lanes on their inlet sides and air lanes on their exit sides, a plurality of horizontally inclined condensate guiding plates across said tube belt and inclining downwardly towards said steam lanes, said condensate guiding plates provided for receiving the condensate from the section of tubes immediately above and discharging said condensate into the steam entering the tube belt from the steam lanes, and vertical splash plates extending longitudinally through the condenser in certain of said steam lanes.

In testimony whereof I affix my signature.

CHARLES E. LUCKE.
